METHOD FOR NEUTRALIZING OBNOXIOUS RADIATION

Rudolf Alberti, Waschegrund 461, St. Andreasberg, Germany

Filed Sept. 30, 1957, Ser. No. 687,316

Claims priority, application Germany Oct. 1, 1956

4 Claims. (Cl. 210—24)

The present invention relates to a method and apparatus for neutralizing or eliminating radioactive isotopic waste.

One of the most important problems of modern science and industry concerned with radioactive materials as used in atomic reactors, scientific laboratories, hospitals, and various other places is the elimination of the waste of such materials which is still sufficiently radioactive to form a source of danger. Although there have been various proposals dealing with the questions of decontaminating water which has become infected with radioactive matter, and of storing, transporting and finally eliminating the "atomic waste," these proposed methods are still quite inadequate and largely very uneconomical. Particularly for eliminating the radioactive isotopic waste water and other waste substances accumulating in laboratories and hospitals, where the many smaller individual amounts of such substances are produced at different times and points might by themselves not be regarded as really dangerous, there has so far been no proposal of any method which is suitable for eliminating or decontaminating the respective liquid or other substances at such low cost and also so easily and safely, particularly in view of the frequent carelessness of persons working with such dangerous waste materials, that such method would be really practicable.

It is the principal object of the present invention to provide a new method which is simple and easily applicable for quickly and effectively converting radioactive isotopic waste, and particularly such waste as may be contained in a dissolved or suspended state in watery liquids, into a form in which it may be handled, stored, transported, and finally and completely eliminated more easily and simply, with less danger, and at a lower cost than possible according to the previous methods.

The present invention takes advantage of the well-known property of materials which have a high density and a specific gravity of more than 4 of being relatively impermeable to and shielding against radiation, and it consists in a method of neutralizing radioactive isotopic waste or rendering the same harmless by applying materials of the mentioned kind in a pulverized condition for absorbing finely distributed isotopic waste. The materials which are especially suitable for this purpose are, for example, heavy metals and/or their compounds, lead, barium compounds, heavy spar, finely ground lead ores and iron ores, ferrous minerals, magnetite, iron dust, lead dust, galena, cinnabar, and bismuth compounds such as, for example, the finely pulverized bismuthum subnitricum and the like used for pharmaceutical purposes. Even pulverized slag containing heavy-metal oxides and therefore of a relatively high specific gravity may be used for this purpose. A very inexpensive absorbing material which is very suitable for the purposes of the invention is finely pulverized barite, especially also in the form of a dried sediment or sludge such as accumulates in large quantities in barite upgrading and refining plants,

2

for example, with a content of 80 to 90% of BaSO_4 . All such radiation-resistant materials may also be applied either by themselves or mixed with each other or with other materials.

If the isotopic waste is contained in liquids, for example, in a suspended or dissolved state, the finely ground radiation-resistant powder, for example, pulverized barite, may be used for absorbing these liquids. Therefore, if the radioactive-contaminated liquid is thus mixed with the powder, the protection attainable in all directions by a certain amount of pulverized barite or the like may be realized much more economically if it would be applied directly and within the volume of the respective liquid rather than if the same amount of barite is used, for example, in the form of masonry for screening off the entire radiation of the unmixed liquid. Calculation and experiments show that for attaining a certain degree of protection in all directions by means of barite, the amount of this material, applied in the form of screening walls around the liquid containing the isotopic waste will have to be three to four times as much as if it is used according to the invention in a finely pulverized form for directly absorbing the radioactive liquid. The all-around protection attainable according to the invention is therefore not only applied more easily and economically but it is also much more effective.

The method according to the invention may be applied, for example, for the purpose of neutralizing, removing, and storing radioactive sewage and waste water of any kind, for instance, from atomic reactors. This method may be carried out, for example, in a pool method in which the collected waste water is mixed with a sufficient quantity of a barite sludge to absorb the water. By grinding such sludge by means of iron balls to a degree of fineness of, for example, 80 to 90% below 2μ , it is possible to increase its absorptive capacity to such an extent that, for example, an amount of 10 to 20 tons of barite sludge will be entirely sufficient for safely storing a quantity of 9000 liters of waste water, which accumulates each day from the operation of an atomic reactor, until the short-lived radiation of this water which is especially dangerous has faded away. The high barite content reduces the radiation of the absorbed radioactive liquid to a considerably greater extent than if it is mixed, for example, only with argillaceous substances which might be added to facilitate its handling. Since the barite sludge also does not combine with the water as firmly as argillaceous substances, but primarily by surface absorption, such sludge saturated with the isotopic liquid may again be dried much more easily and without danger, for example, after the short-lived radiation has faded off after the material has been stored for a quarter to a half year, whereupon the same material may again be used after the period of dangerous radiation has expired.

For determining the amount of protection attainable by the method according to the invention as above described, that is, by absorbing the radioactive liquid in a radiation-absorptive powder, the following comparative experiments were carried out:

First the radiation was measured which emanates from a certain quantity of a radioactive liquid. This liquid was then absorbed by a finely ground, dry barite sludge consisting of 90% of BaSO_4 and 10% of argillaceous additions. The sludge mixture required for absorbing the particular amount of liquid applied in the experiment had a volume of $20 \times 20 \times 20 \text{ cm}^3$. This mixture was again measured to determine its radiation, and such measurement was carried out under the same conditions and at the same distance as the first measurement of the radiation of the liquid alone. The

radiation of the mixture of liquid and sludge amounted to only 31% of the radiation of the liquid alone.

The use of the radiation-resistant properties of the pulverized material, for example, magnetite or barite powder, which is intimately intermixed with the finely distributed isotopic matter may also be combined with the effect of other known materials which in the event that the isotopic waste is in a state of suspension, will filter out these suspended particles from the liquid or which in the event of radioactive ions being dissolved in the liquid, will remove these ions from the contaminated water by the action of ion exchangers, for example, that of argillaceous substances of a type similar to montmorillonite or of synthetic-resin ion exchangers. According to the present invention, the pulverized protective material, for example, finely pulverized barite, may also be used either alone or in combination with other filtering materials as a filling or filtering apparatus, trickling towers, or the like in which contaminated liquids are freed of isotopic waste particles which are suspended therein. Similarly it is possible to apply a finely pulverized protective material such as pulverized barite or the like in combination with ion exchangers of the mentioned kind as a charge for decontamination plants in which dissolved radioactive ions are to be removed from contaminated water. The amount of the additions of radiation-resistant materials to be contained in the filling materials of the filtering apparatus or ion-exchangers is limited in the upward direction by the maximum which does not as yet considerably impair the filtering or ion-exchange effect and which may in each individual case be easily ascertained by experiment. For filtering purposes it is thus, for example, often possible to use a layer of pure barite of a suitable fine granular size. The lower limit in the amount of these additions is approximately that where a further increase in the radiation-resistant effect can no longer be expected as seen from the standpoint of economy, required space, or expenditure as compared with a filtering or ion-exchange material which does not contain any special radiation-resistant additions, that is, for example, at a content of 50% of barite in the absorptive layer.

The residue accumulating in the filtering or other decontamination apparatus may then be solidified in a manner known as such by baking the same in a kiln, to form a ceramic body or by means of hydraulic cementing agents to form bodies which are of sufficient strength to be transportable. The fine protective particles of barite or other materials which are deposited in these bodies then extensively screen off the radiation which tends to emanate from these bodies in all directions so that, for example, the handling and transporting of the clay columns which have been formed by being baked and which contain the isotopic matter can be carried out with considerably less danger than previously was possible.

Instead of enclosing the radioactive waste products in transport containers made of hydraulically hardening cement or the like which are then sunk into the sea, as was previously done, it is much more advantageous if, according to the invention, a mixture of finely ground dry barite powder, a pulverized iron oxide, or other heavy-metal mineral together with an amount of cement sufficient for setting the same is used for absorbing the liquid which is to be eliminated. The body which is thus formed of barite and cement may then have a barite content of, for example, 50 to 95%, since a cement content of as little as 5% or less is often sufficient to produce blocks which are sufficiently solid to be transported. The upper and lower limits of the content in radiation resistant materials are determined by the same principle as previously stated with respect to the amount of such additions in filling materials for filters or ion exchangers. Due to its uniformly distributed contents in barite or other protective materials, the block thus

produced will emit considerably less radiation than the cement blocks used up to the present time for sinking atomic waste products. Furthermore, their content in highly absorptive, finely ground barite also enables such blocks which are to be sunk to absorb a greater volume of contaminated liquid than the blocks previously used.

The present invention also permits the construction of combined decontamination apparatus or plants which, in a manner similar to drip filters, contain montmorillonite, as well as barite sludge or pulverized heavy-metal minerals to serve as filtering, absorptive, and ion-exchange material.

At any rate, the sludge or solid bodies formed by the use of finely pulverized barite or similar material with the finely distributed isotopic matter absorbed therein may be stored with much less danger and requires less additional protective measures than the isotopic waste would require either by itself or when mixed with materials of a lower specific gravity than barite or other radiation-absorbent substances. During the time while the most dangerous short-lived radiation fades off to a strength below the danger point the ionizing rays, particularly the alpha, beta, and gamma rays are also extensively shielded from penetrating toward the outside. A further advantage of the use of the mentioned pulverized radiation-resistant materials, for example, barite powder, for absorbing the radioactive liquid, as compared with allowing such liquid to stand by itself until the radiation has faded off to a point below the danger limit, also consists in the fact that the danger will be fully prevented that the liquid might seep into the ground. Also, instead of allowing the radioactive waste to stand in lead containers, as is still frequently done, and then to drop such containers into the sea, it is also much safer and more convenient to collect the waste products in chambers which are filled with barite sludge or the like until the dangerous radioactivity has faded off. If it should then be necessary to transport the waste to a safe place because the radiation might continue to exist for a greater length of time, such transportation will also be much easier and less dangerous if the waste products are intimately mixed with the barite powder or the like and are thus diluted, as well as screened from the outside.

The degree of pulverization and the absorptive capacity of the materials, such as heavy minerals, barite, and the like used for absorbing the watery isotopic matter is preferably determined in each case by experiment in accordance with the particular screening effect required.

It is another object of the invention to apply the method according to the invention in laboratories or similar places in which radioactive liquids are used, and to provide suitable vessels which are filled with dry pulverized radiation-absorbent materials such as a fine barite powder and are kept quickly available so that in the event some of these radioactive liquids might be spilled or splashed, the protective material may be immediately poured over the source of danger and the radioactive liquid will thus be immediately absorbed by the barite or similar powder and may then be quickly and easily removed therewith. Consequently, it is no longer necessary to absorb or wipe off the dangerous liquid with rags which then have to be disposed of, or to flush it away with water which might reduce the concentration of the spilled radioactive substances but, in turn, might contaminate the sewage and would actually not fully eliminate the danger. Such vessels filled with radiation-absorbent powder, for example, barite powder, and provided with a cover and a bail or handle should be readily available at all points where radioactive liquids might possibly be spilled or splashed. For this purpose it has also been found very advisable to use a strongly colored absorbent powder such as, for example, the above-mentioned cinnabar, which when poured over the splashed radioactive liquid to absorb the

same, will permit the danger spot to remain conspicuous until it can soon thereafter be removed entirely.

The finely pulverized barite or the like may according to the invention also be used in hospitals, either alone or in combination with the usual absorptive materials such as ground peat, for absorbing and removing feces which are radioactively contaminated. Such removal of the dangerous matter after adding an adequate amount of radiation-absorbent powder thereto is much safer and more complete than the methods previously used.

A further important application of the pulverized protective materials according to the invention consists in their use as a cleansing material for cleaning and scrubbing vessels, crucibles, and the like which have been used for producing pulverulent or pasty materials and are soiled by isotopic residues. Such cleansing material may consist solely of the pulverized material according to the invention, for example, barite powder or granular barite mixtures, or of such material in combination with the usual mechanically or chemically active agents.

A suitable absorbent material according to the invention may, for example, be produced by the preparation of a barite sludge which consists of the finest ingredients attained in the upgrading or refining of barite which have only a small clay content, for example, up to 2%, but cannot be utilized for painting purposes. The basic material may also consist, for example, of a purified sludge accumulated from the process of washing the barite and containing a slightly higher percentage in argillaceous ingredients. Such sludge which is accumulated in pools is then dug out therefrom and wet-ground in tubular ball mills until it has attained a granular size of, for example, 90% below 2 μ . The mass is then dried and disintegrated, whereupon it is ready to be applied for the purposes according to the invention as above described. Residual or waste sludge may in some cases also be used as an addition to cement without being ground, and so-called refining sludge may in most cases be utilized directly, either with or without being additionally ground.

Further objects, features, and advantages of the present invention will appear from the following short description of suitable apparatus and appliances for neutralizing and eliminating radioactive isotopic waste, a few examples of which are illustrated in the accompanying drawings, in which—

Fig. 1 shows a bucketlike container for suitably holding the radiation-absorbent powder according to the invention;

Fig. 2 illustrates a small container similar to a sugar dispenser;

Fig. 3 illustrates diagrammatically an apparatus for decontaminating radioactively infected liquids;

Fig. 4 shows a solidified body of finely divided radiation-absorbent material according to the invention for storing or transporting the radioactive substances to be eliminated; while

Fig. 5 illustrates a hydraulically-set block which largely consists of the protective material according to the invention.

Referring to the drawings, Fig. 1 illustrates a bucket-like container 1 of a handy size with a handle 2 and a cover 3, which is suitable for use in laboratories and the like in which isotopic substances are being used. The container is designed to hold a filling 4 of dry, finely pulverized barite or other suitable radiation-resistant powder. It should be kept in a quickly accessible place so that if some of the radioactive liquid used in the laboratory might be spilled or splashed, the dry powder can be quickly poured from the container over the spilled liquid so that the same will be immediately absorbed by the powder and may then be easily removed at any convenient time without danger.

Fig. 2 illustrates a glass jar 12 similar to a sugar or salt dispenser which is filled with cinnabar powder 14 and provided with a pouring lid 13 through which the powder

may be easily poured directly upon small spots of radioactive liquid. The strong color of the absorptive powder makes the spots conspicuous and facilitates their complete removal whenever the attendant can interrupt his work or after he has completed the same.

Fig. 3 diagrammatically illustrates an apparatus for decontaminating radioactively infected liquids. It consists of a container 5 with a filter plate 6 and a layer 7 resting thereon which consists of a filtering, absorbent, or ion-exchange material, for example, asbestos, montmorillonite, fuller's earth, or the like, and also has a content of approximately 60% of finely distributed radiation-resistant material, such as barite powder, iron oxide, lead sulphide, magnetite powder, or the like. This content in radiation-resistant material should preferably be not much lower than 50%, and of an amount and a type so that it will sufficiently reduce the outward radiation of the radioactive waste liquid which is inserted into container 5 through the inlet 8 and which runs off in a purified and decontaminated condition through the outlet 9.

Fig. 4 illustrates a solidified body 10 which has been removed from a filter similar to that shown in Fig. 3 and may be easily stored or transported. It may consist of clay, for example, of the group which includes ion-exchanging montmorillonite, with an adequate content in finely ground radiation-resistant material of the type mentioned above which, after being saturated with the isotopic matter to be eliminated, is baked in a ceramic furnace or kiln and is thus solidified. The content in radiation-resistant materials of a high specific gravity is preferably such that the density of the dry ceramic mixture is not lower than approximately 2.5.

Fig. 5 finally illustrates a hydraulically set block 11 which has a cement content of 10% and a remaining content of finely powdered barite or other radiation-resistant material. If the radiation-resistant addition consists of barite, the block will have a specific gravity of 3.5 to 4, while when using magnetite, the specific gravity will be even higher. The water used for setting the cement may be the same as that which is absorbed by the barite or similar material, that is, the radioactively contaminated water which is to be neutralized or eliminated. Another preferred hydraulic mixture which first absorbs the radioactive liquid and then utilizes the same for setting the mixture consists of

70% by weight of dry, finely pulverized barite sludge with a content of 90% in BaSO₄,
20% by weight of cement, and
10% by weight of bentonite.

The density of the dry hydraulic mixtures should preferably be no less than 2.8.

The radiation-resistant materials, which according to the invention are to be applied in a pulverized condition either alone or in combination with other materials such as filtering materials, absorptive clay, hydraulic or other setting agents, or the like for the purpose of absorbing the finely distributed isotopic substances, may consist of the same materials which have already been used prior to this invention as radiation-resistant materials, particularly such materials with a specific gravity of at least 4. This primarily includes heavy minerals such as barite and heavy-metal compounds. Since such heavy mixtures often contain more or less amounts of lighter ingredients, for example, clay as contained in barite sludges, the dry mixture may be given a minimum density (not volumetric weight) of 3.5.

Although my invention has been described with reference to the preferred application of the finely pulverized materials for absorbing radioactive substances which are dissolved or suspended in liquids and for reducing the radiation thereof toward the outside, I wish to have it understood that it is in no way limited to such application and to the details thereof but is capable of

numerous modifications within the scope of the appended claims and particularly to the use of these and similar materials in a finely divided form for separating, receiving, and absorbing such radioactive substances from flue and other gases in which they might be suspended.

Having thus fully described my invention, what I claim is:

1. A method of absorbing obnoxious radiation emitted by radioactive waste material contained in water which comprises inserting the water into a mixture of a pulverized radiation-absorbent material having a content of at least 50% of barites and having a further content of a hydraulic setting agent, absorbing said water including said radioactive waste material within said pulverized material, and also utilizing said water for substantially solidifying said mixture by means of said setting agent.

2. A method of absorbing obnoxious radiation emitted by radioactive waste material contained in water which comprises passing the water with the waste material content into a mixture of a hydraulic setting agent and of between 50% and 95% powdered barite, and absorbing the water with said waste material within said powdered barite while also using the water for substantially solidifying said mixture by means of the setting agent.

3. A method of absorbing obnoxious radiation emitted by radioactive waste material contained in water which comprises passing the water including its waste material content into a mixture comprising a hydraulic setting agent, between 80% and 90% powdered barite, 90% of which at least is below 2 microns in diameter, and an argillaceous substance, and absorbing the water with said waste material within said powdered barite and

said argillaceous substance while using the water for substantially solidifying said mixture by means of the setting agent.

4. A method of absorbing obnoxious radiation emitted by radioactive waste material contained in water which comprises passing the water with its waste material content into a mixture comprising 70% by weight of dry, finely-pulverized barite with a content of at least 90% in barium sulphate, 20% by weight of cement, and 10% by weight of bentonite, and absorbing the water including said waste material within the pulverized barite and the bentonite while using the water for substantially solidifying said mixture by means of the setting agent.
